UNITED STATES PATENT OFFICE.

FERDINAND L. HOLLY, OF BROOKLYN, NEW YORK.

COLLAR-FASTENER.

1,092,049

Specification of Letters Patent. Patented Mar. 31, 1914.

Application filed November 7, 1912. Serial No. 730,053.

To all whom it may concern:

Be it known that I, FERDINAND L. HOLLY, a citizen of the United States, residing at Brooklyn, in the county of Kings and State 5 of New York, have invented certain new and useful Improvements in Collar-Fasteners; and I do hereby declare the following to be a full, clear, and exact description of the invention, such as will enable others 10 skilled in the art to which it appertains to make and use the same.

This invention relates to collar retaining means and is intended for use in the back of a shirt band to prevent the rear of the 15 collar from riding up and also to prevent the rear of the collar from causing the ill-feeling common to the use of collar buttons at this place.

An object of this invention is to provide a 20 device which when placed in the back of a shirt band will neither become misplaced when removing the collar nor hurt the back of the neck of the wearer.

A further object of this invention is to 25 provide a device which is insertible in the pocket formed in the rear of a collar band of a shirt and which may be securely held therein, which device has a flat tongue intended to pass through the button-hole with- 30 out injuring the same.

A further object of this invention is the provision of a depending tongue positioned in the collar band of a shirt to receive the button-hole in the rear of a collar and to se- 35 curely hold the same in place but to provide easy removal of the collar when so desired without injury to the button-hole thereof.

Further objects will be apparent from the following specification, appended claims 40 and drawings, in which,

Figure 1 is a perspective view of a portion of a collar band of a shirt showing the invention applied thereto, Fig. 2 is an elevation of the device showing its relation to the 45 collar band by dotted lines, and, Fig. 3 is a vertical sectional view through a collar band and collar showing how the device is applied.

This invention is intended to serve a pur- 50 pose which has heretofore been accomplished by collar buttons and by flat fastening means, which collar buttons have proven to be annoying in that the base frequently exerts uncomfortable pressure on the back 55 of the neck of the wearer and which collar buttons injure the button-hole of the shirt

and the collar in the application and removal especially after the shirt has been 60 laundered, then, the flat fastening means heretofore used have been so inserted in the neck band as to become displaced in the removal of the collar.

My invention is intended to be secured to the collar band so that it cannot become displaced in applying or removing a collar and 65 referring more specifically to the drawings, there is shown a plate 10 which has the upper edge thereof straight with rounded ends. Stems 12 depend from the ends of the plate 10 as shown and are curved to present hooks 70 13 and a tongue 14 depends from the center of the lower edge of the plate 10 intermediate of the stems 12 which tongue is offset as at 15. The plate 10 may be flat or may be curved to conform with the curvature of a 75 collar band and the hooks 13 may be bent to a more or less degree than shown as to meet the requirements.

In applying the device the tongue 14 and plate 10 are inverted and pass into the pocket 80 formed between the collar band 16 and the leaf 17 so that the tongue 14 passes through the button-hole 18 when the device is turned to its natural position as shown in Fig. 1. of the drawings, then the lower edge of the 85 leaf 17 is arranged to pass under the hooks 13 so as to lock the device against accidental misplacement. The straight edge 11 also serves to hold the device in the proper position as it fits snugly in the junction of the 90 leaf 17 with the collar band 16.

In applying the collar the stand 19 is positioned so that the button-hole 20 receives the tongue 14 when the collar may be swung to fasten the ends in the front of the 95 neck.

This device may be made as by stamping to produce a form shown in the drawing or it may be made of wire bent to the shape to produce the several parts called for in the 100 specification. Furthermore, this device is practically locked to the leaf of a collar band when properly applied so that accidental raising of the tongue 14 would not permit the displacement of the fastener.

Having thus described my invention, I 105 claim:

1. A collar fastening means comprising a plate having a straight upper edge, stems depending from the ends of the lower edge, 110 said stems being curved in a plane common to said plate, an offset tongue depending

- from the central lower portion of said plate, said stem serving to hold the collar to a collar band and said curved stems locking the device in place.
- 5 2. A collar fastening means comprising a plate adapted to fit in the pocket formed in a collar band, depending stems from said plate, said stems being spaced apart, the outside stems depending from said plate being
- 10 curved in a plane common to the plate to present a hook to engage the lower edge of

a portion of the collar band and the middle stem being bent from and downwardly from said base through the button hole in the collar band.

15

In testimony whereof I affix my signature in presence of two witnesses.

FERDINAND L. HOLLY.
